Attorney.

This is a side elevational view of a fluorescent lamp fixture utilizing the novel hinge structure; Fig. 2 is a cross section, to enlarged scale, along lines 2-2 of Fig. 1; Fig. 3 is a perspective fragment of one part of the hinge structure; Fig. 4 is a perspective fragment of a companion element of the hinge structure cooperable with the part shown in Fig. 3; Fig. 5 is a perspective fragment of the mounting slot for the hinge means of Fig. 3; Fig. 6 is a perspective fragment of the mounting slot for the hinge element of Fig. 4; Fig. 7 is a perspective detail of the novel hinge lug.

Application July 29, 1946, Serial No. 687,003

3 Claims. (Cl. 16—159)

1

This invention relates to a hinge structure of general application, but especially suited to use in certain types of lighting fixture, for example, fluorescent lamp units, particularly, but not exclusively, those adapted for ceiling mounting.

One of the principal objects of the invention is the provision of a hinge structure which is simple and inexpensive to manufacture, and which lends itself peculiarly to the novel dual hinge means to be described hereinafter.

Additional objects are: the provision of hinge means in a lighting fixture, for example, so constructed and arranged that one member of the fixture may be swung relative to another member in either of two opposite directions, or said member may be removed altogether, as the circumstances require, whereby to facilitate the removal, servicing, or inspection of lamp parts, such as the fluorescent tubes in the type of lamp disclosed herein for illustrative purposes; to provide a fluorescent lamp or tube mount of elongated form and constructed so as to mount two or more fluorescent lamps or tubes and also to form a shield or cover for certain cooperating lamp parts, together with a simple and inexpensive hinge means hingedly and removably attaching said lamp mount to a lamp base so that said mount may be pivotally swung relative to the base permitting access to lamp parts; to the provision of hinge means including pairs of perforate lugs having offset mounting feet received in slots and spot-welded or otherwise fixed in position in said slots with the perforations aligned and the lugs spaced to receive a third cooperating lug of identical construction to those of the said pair and similarly mounted on a member to be hingedly connected with the member carrying said pair, there being a hinge pin inserted in the aligned perforations of the several lugs, said third lug being received in between said pair.

Other objects and aspects of novelty of the invention will be understood by reference to the following specification and accompanying drawing, in which:

Fig. 1 is a side elevational view of a fluorescent lamp fixture utilizing the novel hinge structure;

Fig. 2 is a cross section, to enlarged scale, along lines 2-2 of Fig. 1;

Fig. 3 is a perspective fragment of one part of the hinge structure;

This is a side elevational view of a fluorescent lamp fixture utilizing the novel hinge structure; Fig. 2 is a cross section, to enlarged scale, along lines 2-2 of Fig. 1; Fig. 3 is a perspective fragment of one part of the hinge structure; Fig. 4 is a perspective fragment of a companion element of the hinge structure cooperable with the part shown in Fig. 3; Fig. 5 is a perspective fragment of the mounting slot for the hinge means of Fig. 3; Fig. 6 is a perspective fragment of the mounting slot for the hinge element of Fig. 4; Fig. 7 is a perspective detail of the novel hinge lug.

Referring now to the drawing, the fluorescent fixture of Fig. 1 is shown in normal operating position, and may be assumed to be mounted or suspended from an overhead surface, such as a ceiling.

Fig. 4 is a perspective fragment of a companion element of the hinge structure cooperable with the part shown in Fig. 3;

Fig. 5 is a perspective fragment of the mounting slot for the hinge means of Fig. 3;

Fig. 6 is a perspective fragment of the mounting slot for the hinge element of Fig. 4;

Fig. 7 is a perspective detail of the novel hinge lug.

Referring now to the drawing, the fluorescent fixture of Fig. 1 is shown in normal operating position, and may be assumed to be mounted or suspended from an overhead surface, such as a ceiling.

This fixture consists of a top piece 11 to which end members 12 are attached in a known manner, together with a combination reflector and dihedral shield member 13 of approximately V-shaped cross section (Fig. 2), to the opposite side faces 13A, 13B, of which are secured fluorescent tube sockets or adapters 14 (Figs. 1 and 2), there being a pair of said sockets or adapters on each face of said reflector member 13 and each pair mounting a fluorescent lamp tube 15 in known manner.

In accordance with the invention, the reflector-shield means or member 13 is hingedly, and removably, attached to both sides of the top piece or base 11 of the fixture for dual hinge action by utilization of the novel hinge means generally indicated at 16 in Figs. 1 and 2, and shown to larger scale in Figs. 3 and 4 to consist of a pair of apertured lugs 18 having pin or pintle holes 19 and offset mounting feet or projections 20, further described hereinafter; and a companion lug (Fig. 4) 18A receivable in the space between lugs 18 when the latter are mounted in the manner to be set forth, said companion lug 18A being of identical construction to lugs 18, and having a similar mounting offset or foot portion 20A.

The mounting of said lugs on the lamp structure is effected by forming the base member 11 as a channel shaped member with depending edge portions 11A (Figs. 2 and 3), in which are formed openings or slots 11B, as in Fig. 5, wide enough to receive the two mounting feet 20 for each pair of lugs 18, the fixture member 11 being preferably constructed of metal so that said portions 20 may be secured, as by spot welding or the like, to the inner surface of the depending edge portion 11A adjacent said slots.

The mounting of said lugs on the lamp structure is effected by forming the base member 11 as a channel shaped member with depending edge portions 11A (Figs. 2 and 3), in which are formed openings or slots 11B, as in Fig. 5, wide enough to receive the two mounting feet 20 for each pair of lugs 18, the fixture member 11 being preferably constructed of metal so that said portions 20 may be secured, as by spot welding or the like, to the inner surface of the depending edge portion 11A adjacent said slots.

Similarly, the companion hinge element of Fig. 4 has its foot portion 20A passed through a slot 13D formed in an inwardly offset edge portion or projection 13C along each of the upper or free longitudinal edges of the reflector faces 13A and 13B, the member 13 likewise being of metal so that said legs 20A may also be spot welded thereto.

It will be understood that each hinge unit consists of a pair of spaced-apart lugs 18, attached to a first and relatively stationary member and a companion lug 18A received in between lugs 18 and attached to a second and relatively movable member, or vice versa, there being aligned pintle openings in all three lugs of each such unit to receive a hinge pin or pintle such as the cotter pins 17 of Figs. 2 and 3; and it being further understood that there may be any desired number of sets of said hinge units on either side of the lamp fixture, two such sets being illustrated in Fig. 1 on the side of the fixture there shown.

In some types of installation, it may be desirable to have an elongated, common pintle rod 17X, Fig. 1, which passes through the pintle openings of all of the hinge units on a given side of the lamp fixture, so that the removal of this one common pintle pin or rod, quickly conditions the reflector-shield for swinging motion. In the sectional view of Fig. 2, the illustration shows an elongated pintle 17X on one side of the fixture, with individual pins 17 on the opposite side; removal in this case of pintle 17X would permit swinging the member 13 to the dotted-line position for access to the normally shielded lamp part 9, for example. Removal of the pintle pins on the opposite side of the lamp would, of course, permit swinging of the reflector 13 to a position opposite that shown in Fig. 2.

Frequently in the installation of this type of lighting fixture, obstructions of various kinds prevent movement of the reflector in one direction but not in the other, so that the novel dual hinging of the lamp members makes it unnecessary to reverse the mounting of the base portion, or to remove the reflector element altogether, as is necessary in older types of fixtures; moreover, the hinge means itself is of such simple and economically fabricated nature as to render it especially suited to volume production methods, since both the fixture elements 11, 11a, 13, 13C, with mounting slots 11B and 13D, and the hinge members 18, Fig. 7, lend themselves readily to simple die-stamping and upsetting operations.

In the preferred construction, spotwelding of the hinge members to the fixture member, as hereinabove described, is desirable; however, other methods of attachment are contemplated, such as riveting, bolting, crimping, and the like; and these and other modifications in the described construction are considered within the scope of the invention.

In the construction of the hinge member shown in Fig. 7, attention is called to the fact that the leg portion 20 is narrower than the adjoining body portion generally indicated at 18, with the result that a mounting shoulder is formed at the point of juncture between these portions, as indicated generally at 18X; and this shoulder means adds stability and strength of the mounting of the member, as in Fig. 4, by reason of the fact that said shoulder portion rests against the reflector, or other element on which it is mounted, in the region immediately adjoining the slot portions 13D therein.

Modifications as suggested herein, as well as those that may occur to others, are intended

to be within the scope of the invention as defined by the appended claims.

I claim:

1. A hinge member for pintle-pin connection and for mounting particularly on a metal wall member, said hinge member comprising a lug apertured to receive a pintle pin, and said lug having a narrowed leg extending medially from one side thereof to form opposite seating shoulders at the juncture of the leg with said lug, said leg being offset at approximately right angles to its lug at a position spaced from the said one side of the lug a distance approximately equal to the thickness of the wall member on which the hinge member is to be mounted, said leg being adapted to be passed through an opening in the said wall member to seat against a rear face thereof and being adapted to be secured to the said wall member with the corresponding lug shoulders adapted to span said opening to seat against the opposite face of said wall member to stabilize the hinge member thereon.

2. A hinge structure comprising, in combination with a pair of members to be joined, the following improvements, to wit: At least one pair of hinge elements, each element consisting of an apertured lug, each lug having a narrowed leg offset at approximately right angles to the lug and said legs respectively forming opposite shoulders at their respective junctures with the corresponding lugs, said pair of lugs being mounted in spaced juxtaposition on a first one of said members with said legs respectively passed through a single opening in said first member and oppositely directed and engaging a rear wall portion of said first member, with the corresponding shoulders respectively seating against the outer wall portion of said first member adjoining said opening therein to stabilize the lugs, said legs being respectively secured to said rear wall portion, and an identical cooperating hinge element identically mounted on the second of said members and fitted between said pair of lugs on the first member and joined thereto by pintle means through the apertures in all three lugs, each said leg being spaced from the corresponding shoulder an amount equal to the thickness of the member on which the hinge element is mounted as aforesaid, whereby said shoulders are firmly seated against said outer wall portion when the corresponding legs are engaged with the rear wall portion as aforesaid.

3. A hinge structure comprising, in combination with a pair of members to be joined, the following improvements, to wit: At least one pair of hinge elements, each element consisting of an apertured lug, each lug having a narrowed leg offset at approximately right angles to the lug and said legs respectively forming opposite shoulders at their respective junctures with the corresponding lugs, said pair of lugs being mounted in spaced juxtaposition on a first one of said members with said legs respectively passed through a single opening in said first member and oppositely directed and engaging a rear wall portion of said first member, with the corresponding shoulders respectively seating against the outer wall portion of said first member adjoining said opening therein to stabilize the lugs, said legs being respectively secured to said rear wall portion, and an identical cooperating hinge element identically mounted on the second of said members and fitted between said pair of lugs on the first member and joined thereto by pintle means through the apertures in all three lugs, said opening in the first member being of a length

closely approximating the combined thickness of said pair of hinge elements and said cooperating element, and said opening also being of a width closely approximating the width of said legs, whereby to provide a firm interfit of said pair of hinge elements with marginal portions of said opening in the mounting thereof as aforesaid to stabilize the hinge structure.
